H. M. ROSS

BOTTLE SEALING MACHINE

Filed Sept. 28, 1923

UNITED STATES PATENT OFFICE.

HUGH M. ROSS, OF WOODHAVEN, NEW YORK, ASSIGNOR TO ADRIANCE MACHINE WORKS, INC., OF BROOKLYN, NEW YORK, A CORPORATION OF NEW YORK.

BOTTLE-SEALING MACHINE.

Application filed September 28, 1923. Serial No. 665,260.

My invention relates to bottle sealing machines. The principal object of the invention is to provide in machines of that kind improved means for shifting the caps or closures for the bottle or container to operative position in the machine. In machines of this character heretofore constructed the caps are moved to position in the machines by a spring pressed pusher which 10 engages the caps with something of a blow, tending to deform caps and prevent uniformly satisfactory sealing of the containers, especially if the cap is made of relatively thin material. One object of my invention is to obviate this defect.

Other objects of my invention will appear more fully in the following detailed description and appended claims.

The accompanying drawings forming a part of this specification illustrate one embodiment of mechanism containing my invention.

In the drawings,

Fig. 1 is a front view of the mechanism.

Fig. 2 is a side view of a portion thereof.

Figs. 3 and 4 are sections taken on line 3-3 of Fig. 2 and showing the apparatus in different positions; and

Fig. 5 is a side view of the cap pusher.

Referring to the drawings, the sealing head 1 is provided with a sealing gate 2 which is fulcrumed for pivotal movement about the axis of the vertical shaft 3 into open or closed position. The gate 2 is splined to the shaft 3 as shown at 4 so as to rotate with the shaft 3. A coil spring 5 surrounding the shaft 3 and connected at opposite ends with said shaft and a relatively fixed part of the machine tends to 35 rotate the shaft 3 in the direction to effect the closing of the gate 2 against the head 1. The machine comprises a relatively fixed housing 6 provided with a cam slot 7 in which is engaged a roller 8 carried by a 40 collar 9 secured to the shaft 3. As roller 8 rises and falls in the inclined portion of the cam slot 7 during the operation of the machine, the shaft 3 rotates to effect the 45 opening or closing of the gate 2. The opening of the gate is effected by the cam action on the roller 8 of the coating wall of the cam slot 7, which action causes the shaft 3 to be rotated against the torsion of spring 5. To seal the closure inlet 10 when the

gate is closed, the latter is desirably provided with a rubber gasket 11.

The closure may be supplied to closure inlet through a suitable closure supply chute 12 which, as shown, is provided with a retaining pawl 13 which supports the whole 55 line of closures in the chute except when it is uplifted by the head 1 as the same is elevated, the chute 12 being stationary. Before the cap inlet 10 has been moved to register with the closure chute 12, the gate 2 60 has, of course, been moved to open position and out of the way of the chute. When the retaining pawl 13 is elevated a closure enters the inlet 10 and bears against the liquid supply plunger 14. The cap remains 65 in this position until the plunger 14 is elevated after the bottle has been filled after which the closure is thrust by a pusher carried by the gate to a position above the bottle and below the cap sealing throat 15. 70 The skirt of the cap is adapted, upon further downward movement of the sealing head, to be contracted by throat 15 about the rib at the mouth of the bottle to seal the cap in place on the bottle. The apparatus described in the foregoing detailed description is not per se new in this invention. For 75 a more detailed description of the construction and operation of such apparatus, attention is directed to United States patent 80 to Calleson Reissue No. 14,657, dated June 10, 1919.

The cap pusher herein disclosed is so constructed and arranged that instead of striking the cap with a blow it engages the same 90 with but little impact and further tends to avoid deformation thereof by moving laterally thereof during its engagement therewith. Referring to the drawings, the pusher is movable horizontally in an extension 95 16 in the gate or closure 2, its path of movement being at an angle to the cap inlet 10. The pusher comprises a forward cap engaging portion 17 and a rear body portion 18 to which the cap engaging portion 17 is pivoted for movement about a vertical axis, as shown at 19. A spring 20 bearing against the end wall of the extension 16 of the gate or closure 2 and against the body 18 of the pusher tends to move or 100 maintain the pusher so that the cap engaging portion 17 is projected beyond the gate. The body portion 18 of the pusher 105

is formed to partly enclose the spring 20. A spring 21 tends to yieldingly hold the cap engaging portion of the pusher in alinement with the body portion 18 thereof. 5 The outer or projecting end of the cap engaging portion of the pusher is provided with a projection 22 which is arranged to register with a guide shown as in the form of a groove 24 in the bottom wall of the cap 10 inlet 10 when the gate 2 is entirely closed, the groove 24 being arranged so as to be under those conditions in alinement with the path of movement of the projection 22; so that the pusher is adapted to force the 15 cap inwardly of the head to its position above the bottle or container when the liquid supply plunger 14 is elevated in the sealing head. (See Fig. 4.)

In Fig. 3 I have shown in dotted lines the 20 position of the parts during the closing of the gate at the time the pusher first comes into engagement with the sealing head. It will be seen that in this position the projection 22 is to one side of the groove 24. The 25 projection 22 is accordingly held by the head from engagement with the cap; and during the further closing of the gate 2, the sealing head by its engagement with the projection 22 holds the pusher out of engagement with the cap and causes the pusher to be retracted into the housing 16 on the gate 2. When the gate is entirely closed the projection 22, having moved laterally towards the groove 24 during the closing of 30 35 the gate 2, registers with the said groove. The pusher at that time engages the cap, having moved gradually in its lateral movement with respect to the groove 24 into engagement with the cap.

40 Referring to Figs. 3 and 4 it will be seen that as the cap is moved inwardly by the pusher, the cap engaging end of the pusher moves laterally or horizontally with respect to the cap so that instead of exerting all 45 of its pressure in a thrust directly upon one point of the cap the pusher applies its pressure to the cap in a combined lateral and forward movement. The result of the above coaction of the pusher with the cap 50 is to move the latter into position above the bottle cap or seal without the objectionable deformation of the cap.

55 As the groove 24 is not equally distant at every point from the axis of the shaft 3, it is necessary that the projection 22 on the cap engaging portion 17 of the pusher be capable of yielding laterally with respect to the gate 2 when the gate is opened. This 60 lateral yielding is permitted by the pivotal mounting of the portion 17 of the pusher with respect to the body of the pusher; so that upon opening of the gate the portion 17 of the pusher can yield laterally to permit the projection 22 to pass freely along and 65 out of the groove 24. The portion 17 of the

pusher is, as shown, provided with a recess 25 on one longitudinal edge thereof and is cut away as shown at 26 and 27 to permit the desired lateral movement thereof without binding against the gate 2 and without 70 obstruction from the portion 18 of the pusher.

It is to be understood that changes and modifications may be made in the device 75 shown and described without departing from the spirit of my invention and the scope of the appended claims.

Having thus described my invention, what I claim as new and desire to secure by Letters Patent of the United States is:

1. The combination with a head having a closure inlet, of means for positioning a closure in said head comprising a closure pusher, means for moving said pusher toward said inlet, and means acting upon 85 said pusher after such movement thereof for arresting the same before engagement thereof with the closure and thereafter releasing the same to permit engagement there- 90 of with the closure.

2. The combination with a head having a closure inlet, of means for positioning a closure in said head comprising a closure pusher and a movable carrier for moving the same toward said inlet, said head and pusher having coating means for arresting the pusher during the movement of said carrier and releasing the same when said carrier has reached a predetermined later position.

3. The combination with a head having a closure inlet, of means for positioning a closure in said head comprising a closure pusher and a pivoted carrier movable about a vertical axis for moving the pusher towards said inlet, said head and pusher having coating means for arresting the pusher during the movement of said carrier and releasing the same when said carrier has reached a predetermined later position.

4. The combination with a head having a closure inlet, of means for positioning a closure in said head comprising a spring pressed closure pusher and a movable carrier for moving the same towards said inlet and for closing said inlet, said head having a fixed stop for arresting the pusher during the movement of said carrier said stop being arranged to release the pusher when said carrier has reached a predetermined later position.

5. The combination with a head having a closure inlet, of means for positioning a closure in said head comprising a closure pusher and a carrier pivoted about a vertical axis 125 for moving the pusher towards said inlet, said pusher having a plurality of sections connected for pivotal movement about an axis parallel to the pivotal axis of said carrier, said head having means for arrest- 130

ing the pusher during the movement of said carrier and releasing the same when said carrier has reached a predetermined later position.

5 6. The combination with a head having a closure inlet, of means for positioning a closure in said head comprising a spring pressed closure pusher and a movable carrier for moving the same towards said inlet, 10 said pusher being movable relatively to said carrier in a direction inclined laterally to said closure inlet, said head and pusher having coacting stop means for arresting the pusher during the movement of said carrier 15 and releasing the same when said carrier has reached a predetermined later position.

7. The combination with a head having a closure inlet, of means for positioning a closure in said head comprising a closure 20 pusher and a pivoted carrier for moving the same towards said inlet, said pusher having a body portion movable relatively to said carrier in a direction inclined laterally to said closure inlet when said carrier is in 25 its innermost position and having also an outer closure impinging portion connected to said body portion for pivotal movement about an axis parallel to the pivotal axis of said carrier, said head having means for 30 arresting the pusher during the movement of said carrier and releasing the same when said carrier has reached a predetermined later position.

8. The combination with a head having a 35 closure inlet, of means for positioning a closure in said head comprising a closure pusher and a pivoted carrier for moving the same towards said inlet, said pusher having a body portion movable relatively to 40 said carrier in a direction inclined laterally to said closure inlet when said carrier is in its innermost position and having also an outer closure impinging portion connected to said body portion for yieldingly resisting 45 pivotal movement about an axis parallel to the pivotal axis of said carrier, said head having means for arresting the pusher during the movement of said carrier and releasing the same when said carrier has 50 reached a predetermined later position.

9. The combination with a head having a closure inlet, of means for positioning a closure in said head comprising a closure 55 pusher and a carrier pivoted about a vertical axis for moving the pusher towards said inlet, said pusher including a member movable relatively to said carrier about an axis parallel to the pivotal axis of said carrier, said head having means for arresting the 60 pusher during the movement of said carrier and releasing the same when said carrier has reached a predetermined later position.

10. The combination with a head having a closure inlet, of means for positioning a closure in said head comprising a closure 65

pusher and a pivoted carrier for moving the same towards said inlet, said pusher including a member mounted for movement relatively to said carrier in a path inclined laterally to said closure inlet when said carrier is in its innermost position and also for movement about an axis parallel to the pivotal axis of said carrier, said head having means for arresting the pusher during the movement of said carrier and releasing the 75 same when said carrier has reached a predetermined later position.

11. The combination of a head having a closure inlet provided with a guide, and means for positioning a closure in said inlet comprising a closure pusher, a carrier for said pusher hinged to carry said pusher towards and away from said inlet, means tending to hold said pusher in projected relation to said carrier, and means carried by 80 said pusher and arranged to be arrested by said head to retract the pusher relatively to the carrier during inward movement of said carrier but to be released for entry into 85 operative relation to said guide to effect the 90 release of the pusher when the carrier has reached a predetermined position in its inward movement.

12. The combination of a head having a closure inlet provided with a guide inclined laterally thereto, and means for positioning a closure in said inlet comprising a closure pusher, a carrier for said pusher hinged to carry said pusher towards and away from 95 said inlet, said pusher being movable relatively to said carrier along a path out of register with said guide during inward movement of the carrier but adapted to register therewith when the carrier reaches a predetermined position in its inward 100 movement, means tending to hold said pusher in projected relation to said carrier, and means carried by said pusher and arranged to be arrested by said head to retract the pusher relatively to the carrier 105 during inward movement of said carrier but to be released for entry into operative relation to said guide to effect the release of the pusher when the carrier has reached 110 said predetermined position.

13. The combination of a head having a closure inlet provided with a guide, and means for positioning a closure in said inlet comprising a closure pusher, a carrier for said pusher hinged to carry said pusher towards and away from said inlet, said pusher including a member movable relatively to said carrier along a path out of register with said guide during inward movement of the carrier but adapted to register therewith when the carrier reaches a predetermined position in its inward movement, means tending to hold said pusher in projected relation to said carrier, and means carried by said pusher and arranged 115 120 125 130

to be arrested by said head to retract the pusher relatively to the carrier during inward movement of said carrier but to be released for entry into operative relation to said guide to effect the release of the pusher when the carrier has reached said predetermined position, said member having a yieldingly resisted lateral movement rela-

tively to said carrier to avoid binding of said pusher carried means in said guide during the movement of the carrier away from the head. 10

In testimony whereof, I have signed my name to this specification.

HUGH M. ROSS.
